CLAIM

The ornamental design for a pocket perfume atomizer, as shown and described.

DESCRIPTION

FIG. 1 is a front elevational view of a pocket perfume atomizer showing my new design;

FIG. 2 is a rear elevational view thereof;

FIG. 3 is a perspective view thereof;

FIG. 4 is a side elevational view thereof;

FIG. 5 is a bottom plan view thereof;

FIG. 6 is a top plan view thereof;

FIG. 7 is a front elevational view of a pocket perfume atomizer showing a modified form of my new design;

FIG. 8 is a rear elevational view thereof;

FIG. 9 is a perspective view thereof;

FIG. 10 is a side elevational view thereof;

FIG. 11 is a bottom plan view thereof; and

FIG. 12 is a top plan view thereof.
